CONTACT LENS CASE

Frederic M. Kirchner and Allan A. Isen, Buffalo, N.Y.,
assignors to Griffin Laboratories Incorporated, Buffalo,
N.Y.

Filed Sept. 25, 1970, Ser. No. 25,189

Term of patent 14 years

Int. Cl. D16—06

U.S. Cl. D57—1

FIG. 1

FIG. 2

FIG. 3

FIG. 5

FIG. 6

FIG. 4

FIG. 7

FIG. 8

FIG. 9

FIG. 10

FIG. 1 is a perspective view of a contact lens case showing our design as embodied in a case for the lens for the right eye and showing the case closed;

FIG. 2 is a perspective view thereof showing the case opened;

FIG. 3 is a front elevational view thereof;

FIG. 4 is a top plan view thereof;

FIG. 5 is a side elevational view thereof, both sides being the same;

FIG. 6 is a rear elevational view thereof;

FIG. 7 is a bottom plan view thereof;

FIG. 8 is a front elevational view of the contact lens case of our design embodied in a case for the lens for the left eye;

FIG. 9 is a top plan view thereof; and,

FIG. 10 is a sectional view along line 10-10 of FIG. 8.

The rear, bottom, and side views of the contact lens cases of FIGS. 1 and 8 are the same.

We claim:

The ornamental design for a contact lens case, as shown and described.
